UNITED STATES PATENT OFFICE

124,818

DESIGN FOR A HOG HOLDER

Walter N. Harness and Ora A. Swartz,
Bunceton, Mo.

Application July 17, 1940, Serial No. 93,724

Term of patent 14 years

To all whom it may concern:

Be it known that we, Walter N. Harness and Ora A. Swartz, citizens of the United States and residents of Bunceton, in the county of Cooper and State of Missouri, have invented the new, original, and ornamental Design for a Hog Holder, of which the following is a specification, reference is had to the accompanying drawing, forming part thereof, in which the figure is a perspective view of a hog holder, showing our new design.

We claim:

The ornamental design for a hog holder, as shown.

WALTER N. HARNESS.
ORA A. SWARTZ.
